CLAIM

The ornamental design for a tamper evident label for an IV bag, as shown and described.

DESCRIPTION

FIG. 1 is a front perspective view of a first embodiment of a tamper evident label for an IV bag;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken line portion of the figure drawings is included to show portions of the article that form no part of the claimed design.

1 Claim, 1 Drawing Sheet(56)
